UNITED STATES PATENT OFFICE

2,231,135

WIPER ATTACHMENT FOR METALWORK-
ING MACHINESMalcolm G. Murray, Ellwood City, Pa., assignor
to National Tube Company, a corporation of
New Jersey

Application September 8, 1937, Serial No. 162,922

3 Claims. (Cl. 15—97)

This invention relates to cleaning continuous tube or wire stock, and particularly to an improved wiping device to be used in connection with metal-working machines for cold-working this class of material.

When cold-working metal it is common practice to lubricate the work at some stage during the working so as to keep the working-rolls and the work at a cool, even temperature. The lubricant usually used is a tallow "dope," or oil, or some other cold-drawing lubricant. Any lubricant tends to stick to the metal and, of course, has to be removed, for various reasons, before it is sent to the trade.

It is common practice to remove this coating of lubricant by allowing a thin stream of kerosene or other solvent to run over the work which tends to soften and dilute the lubricant. The lubricant, together with the kerosene, or other solvent, is then later removed by wiping the work by hand. This, of course, is an extra operation and very inefficient.

It is one of the objects of this invention to provide an automatic means for continuously removing the lubricant from continuously drawn work, and thus to eliminate the manual wiping thereof.

It is another object of my invention to provide a simple and inexpensive adjustable wiping device which can be easily attached to a machine and which is very efficient in its operation.

Various other objects and advantages of this invention will be more apparent during the course of the following specification and will be particularly pointed out in the appended claims.

In the accompanying drawing I have shown, for the purpose of illustration, one embodiment which my invention may assume in practice.

In the drawing:

Figure 1 is a plan view of part of a straightening machine as used in connection with metal-working machines embodying my improved wiping device;

Figure 2 is an end view of the machine shown in Figure 1;

Figure 3 is an isometric view of my improved wiping device unassembled showing the relation of the different parts; and,

Figure 4 is an isometric view of my improved wiping device showing the parts assembled.

This invention is shown on a conventional type straightening machine, such as used in connection with tube or round stock metal-rolling machines. Such a straightener consists of skewed-rolls 5 and 6 which simultaneously im-

part a combined rotary and longitudinal movement to the continuous length of tube stock 1 to give it a helical-like forward movement as it passes through the machine.

My improved wiping device consists of a bracket member having a flat plate-like portion 8 and having a cylindrical sleeve-like portion 9 integrally arranged therewith. The bracket is attached by means of the machine screws 10, to the end journal box 6a of the straightener, as shown in Figures 1 and 2 or can be attached to the frame or to any other rigid part of the machine in any suitable manner.

A post member 11, having a flat end portion 12 and a threaded portion 13, is adjustably held in the cylindrical portion of the bracket by the locking-nuts 14. The wiper blade 15, having slotted holes 16, is adjustably secured to the flat end portion of the post by the plate-washer 17 and the bolts or studs 18.

The wiper blade can be made from any pliable or yielding material which will not absorb oil and which has satisfactory wearing qualities. Synthetic rubber seems to be a most satisfactory material to use.

It will readily be seen that this wiping device, due to its construction, can be readily adjusted sidewise by means of the nuts 14 in a plane perpendicular to the path of travel of the tube through the machine to take care of various sizes of stock, and it also can be adjusted angularly by turning the post to the most satisfactory position for the best cleaning results. The holes in the wiper block are slotted in order that the wiper blade may be adjusted to position in the post in case of wear.

In operation it will be seen that, as the tube stock leaves the straightening machine, it comes in contact with the wiper blade and, due to the helical-like forward movement of the tube out of the machine, the entire outer surface of the tube is thoroughly cleaned and freed from grease.

While I have in this application specifically described one embodiment which my invention may assume in practice, it will be understood that this embodiment is merely for the purpose of illustration and description and that various other forms may be devised within the scope of my invention, as defined by the appended claims.

I claim:

1. A device for cleaning tubular stock and the like comprising a pliable rubber wiping blade, a threaded post member, means for adjustably holding the rubber blade on one end of said post, a bracket member adapted to be attached to the

frame of a metal working machine, said bracket member having a cylindrical portion adapted to receive said threaded post, and an adjusting nut positioned on the threaded portion of said post at each end of the cylindrical portion of the bracket to hold said post member adjustably therein.

2. A wiping device of the class described comprising a pliable wiping blade made from a resilient material, means for holding said wiping blade, means for adjusting the position of said wiping blade in said holding means whereby the wiping blade can be adjusted therein so that the proper amount of the wiping blade is exposed and extends therefrom, means for rotatively supporting said holding means so that said holding means can be adjusted about a fixed axis relative thereto to any desired rotative position, said holding means being so arranged relative to said supporting means that the holding means is also adjustable in a plane along said axis, and means

for securely locking said holding means in any particular adjusted position so as to prevent unintentional movement thereof.

3. A wiping device of the class described comprising a post member, a pliable wiping blade made from resilient material arranged on one end of said post member, means for adjusting the position of said wiping blade in the end of said post member whereby the wiping blade can be adjusted therein so that the proper amount of wiping blade is exposed and extends therefrom, means for rotatively supporting said post member so that said post member can be adjusted about the fixed axis of said post member to any desired rotative position, said post member being so arranged relative to said supporting means that the post member is also adjustable in a plane along said axis, and means for securely locking said post member in any particular adjusted position so as to prevent unintentional movement thereof.
